CIGARETTE FEEDING MECHANISM

Walter Everett Molins, Deptford, London,
EnglandApplication June 30, 1933, Serial No. 678,490
In Great Britain July 11, 1932

2 Claims. (Cl. 198—31)

This invention relates to cigarette making machines, and has for its object to provide a device for delivering cigarettes from a continuous rod cigarette machine in two or more rows on to a conveyor or conveyors which convey them to a packing machine.

For example, in some well known types of packing, the cigarettes are packed into the packages in quantities of twenty, and in three layers 10 consisting, for instance, of two rows of seven and one row of six cigarettes.

Where it is proposed to transfer cigarettes from the cigarette delivery band direct into a cigarette packing machine, it will be understood 15 that it would be convenient for the cigarettes to be delivered in three rows on to the cigarette catcher band, one of such rows to contain cigarettes in the proportion of six cigarettes to seven cigarettes in each of the other two rows.

According to the present invention there is provided a cigarette delivery device for the purpose specified, comprising a rotatable drum for each row furnished with deflecting blades on its periphery which are arranged to sweep the cigarettes on to the band, each drum having a 20 number of blades equal to, or a multiple of, the number of cigarettes in the corresponding layer of the packet.

The invention will be more particularly described with reference to the accompanying drawings, in which:—

Figure 1 is a front elevation of the delivery end of a cigarette making machine showing the invention applied thereto.

Figure 2 is a plan of Figure 1.

Figure 3 is a sectional end elevation of Figure 1 taken in the direction of the arrow A, and for the sake of clearness, only the blades on drum 4 are shown.

Figure 4 is a fragmentary view in the direction of the arrow A in Figure 1, and drawn to a larger scale, and also showing the relative position of the deflecting blades on the drum 2, 3 and 4.

Figure 5 is a diagram similar to Figure 3, but showing details omitted from that view.

Referring to the drawings,—the cigarettes are cut from the rod by an apparatus located at the right-hand end of Figure 1, but not shown on the drawings and are discharged to a continuously moving tape or belt 1 having a uniform speed, which belt, together with the roller 12 separates the cut cigarettes from one another so that they are equi-distantly spaced apart from one another. The separate cigarettes travel

along the tape or belt and are swept therefrom by one of the deflector drums 2, 3 or 4 as hereinafter explained. The cigarettes are deflected on to a travelling belt 5 which carries them in the direction of the arrow to the bed of the packing machine. 5

In the present case the cigarette packets are to contain twenty cigarettes consisting of top and bottom rows of seven cigarettes with a row of six cigarettes between, and therefore, the deflector drums are provided with a total of twenty deflector plates 6, distributed in the following manner:—

Number 2 drum is fitted with seven deflector blades and will consequently discharge seven 15 cigarettes from the tape 1 on to the belt 5 each time it makes a complete revolution.

No. 3 drum has six blades and will consequently discharge six cigarettes in the same time, 20 while No. 4 drum is fitted with seven blades.

For convenience of manufacture and setting, the drums have twenty equally spaced grooves 7 into certain of which the blades are fitted and secured by small screws, and each drum is capable of being adjusted angularly and axially upon 25 the shaft 8 for the purpose of setting the apparatus, the drums being locked in position by screws 9.

When the drums rotate, the vanes sweep the cigarettes from the tape 1 on to the belt 5, and during this movement, the cigarettes pass between top springs 9a and bottom springs 10 which assist in maintaining the alignment and checking the speed so that the cigarettes fall on to the belt 5 in proper formation. These springs are of particular importance where it is desired to pack cigarettes of square or non-circular shape as these 30 may be delivered on to the belt 5 without being turned over during this movement.

The blades 6 are preferably disposed about the drums in such a manner that the first cigarette of a particular batch to be packed is discharged on to the belt 5 by a blade on the drum 4, the next cigarette by a blade on the central drum 3 and the next by a blade on the drum 2, this sequence 40 being repeated throughout the working of the machine, with the exception that during each revolution of the drums, the central drum 3 will miss one cigarette, since it has only six blades to the seven blades on each of the drums 2 and 4. 50 The majority of the blades are, therefore, spaced apart on the drums in the manner shown in the upper part of Figure 3, that is, with two empty grooves between each pair of blades, but in the case of the centre drum 3 only six blades are used, 55

leaving, therefore, four grooves between one pair of blades.

The left-hand drum No. 4 is as shown in Figure 3 and has an extra blade 46b, whilst the right-hand drum 2 is somewhat similarly arranged except that the extra blade 25b on drum 2 is located next to the blade 6a on drum 2 as shown in Figure 5. Thus in Figure 5 the blades on drum 2 are shown in dotted lines, those on drum 3 in fine lines, and those on drum 4 in thick black lines. By this arrangement the delivery of cigarettes to each of the rows is consecutive in order to keep each row filled and to prevent the formation of large gaps in the rows which would occur if each drum swept its complement of cigarettes on to the band in the form of a group of successive cigarettes.

It will be seen that at each rotation of the three drums six cigarettes in each row will be swept by the evenly spaced blades 6a in groups of three, one cigarette for each row. The extra cigarettes in the two outside rows, that is, the seventh cigarette in each of these two rows are swept off by the seventh blades 26b and 46b on drums 2 and 4, respectively. The timing of the blades as previously stated may be seen in Figure 5, the relative speeds of rotation of the shaft 8 and drums 2, 3 and 4 to the cigarettes delivered by the belt 1 to the deflecting positions being such that for each cigarette delivered from the cut-off, the shaft 8 and drums turn through an angle of 18° or one twentieth of a complete rotation and during such period the tape 1 advances a cigarette from one drum position to the next. The belt 1, the roller 12 and the shaft 8 are all driven in suitable timed relationship from the main drive of the machine.

It will be appreciated that the time taken by the cigarettes to travel from one drum position to the next has to be accounted for when setting the apparatus, and for this reason the blades of the drum 3 are displaced slightly with respect to those of the drum 2 and the blades of drum 4 are correspondingly displaced with respect to those of the drum 3, this effect being clearly shown in Figures 4 and 5 where the blades of all three drums are indicated. In actual operation, the cigarettes are delivered in axial alignment by the belt 1 at definitely spaced intervals, as will be more clearly seen in Figure 2. The drums are so timed that there will be a cigarette opposite each of the drums 2, 3 and 4 at approximately the same time, and these will be swept by the blades 6d, the blades 6d being so set that the blade on the drum 2 meets the first cigarette slightly in advance of the corresponding blade 6d on drum 3, and that in turn, is slightly in advance of the blade 6d on drum 4. This slight delay in time enables the cigarettes to come into their correct position so that the blades on the drums 3 and 4 meet them approximately about their middle. In other words, the displacements between the blades 6d on drums 2 and 3 and between drums 3 and 4 respectively, are only sufficient to allow for the time taken by the cigarettes to travel to the proper position.

After the first group of cigarettes has been deflected by the blades 6d, three more cigarettes have come into position and are deflected by the blades 6e. Again, the blades 6f, 6g, 6h and 6a deflect three cigarettes at a time. After the cigarettes have been deflected by the blades 6a, it will be noticed that a blade 6b is provided on drum 2 close to the blade 6a on drum 2. The spacing of

this blade 6b from blade 6a on drum 2 is only sufficient to allow one cigarette to move into position opposite the blade 6b, and this cigarette is then immediately deflected. After this cigarette is deflected, the cigarettes move on, but there are no deflecting blades until we reach the blade 6b on drum 4. This blade immediately deflects one cigarette, while the other two drums 2 and 3 do not deflect any. Immediately after this blade 6b on drum 4 has deflected this one cigarette, the 10 cigarettes move on, and owing to the fact that the blades 6d are immediately following, the cigarettes can only move a distance from one drum to the next, so that they are all swept practically simultaneously again by the blades 6d. 15

It will be seen from this description of the operation that the blades 6d, 6e, 6f, 6g, 6h and 6a operate to sweep three cigarettes at a time, whereas, the seventh cigarette of the rows deflected by drums 2 and 4 are done at separate times by the 20 blades 6b on drums 2 and 4 respectively.

Alternatively, the blades may be arranged on the drums so as to deliver the cigarettes ready for packing with the row containing six either at the right or left as well as in the middle as 25 above described, and further, that the arrangement of the deflectors may be followed to give any required number in any of the rows, the sole requirement being that the total number of blades shall be equal to the number of cigarettes 30 contained in one packet or a multiple thereof.

It will be understood that any suitable means may be provided for receiving the cigarettes and maintaining them in separate groups, such means entirely depending on the type of packing which 35 is used. Such means do not form any part of the present invention.

What I claim as my invention and desire to secure as Letters Patent is:—

1. For use on a cigarette making machine of 40 the continuous rod type in which the cigarettes issue in axial alignment from a cut-off device on the machine, a cigarette delivery device for delivering the axially moving cigarettes laterally in at least two rows, said delivery device 45 comprising a rotating support having a plurality of sets of rotating deflecting elements, one set for each row, the number of deflecting elements for each row being proportional to the number of cigarettes to be delivered to the apertaining 50 row of cigarettes during one cycle of each set, and all the deflecting elements having the same peripheral speed, the number of deflecting elements in one set being different from the number of deflecting elements in at least one other 55 set.

2. For use on a cigarette making machine of the continuous rod type in which the cigarettes issue in axial alignment from a cut-off device on the machine, a cigarette delivery device for 60 delivering axially moving cigarettes laterally in at least two rows, the said cigarette delivering device having a plurality of sets of rotating deflecting elements supported for movement transversely across the path of the cigarettes, the sets 65 being arranged to rotate in synchronism and in cycles, and the number of deflecting elements in the sets being so arranged that during one cycle of operation the effective total number of deflecting elements of each set which move transversely across the path of the cigarettes is different from the number in at least one other set.
